UNITED STATES PATENT OFFICE

CLARENCE C. BRINLEY, OF HUDSON, NEW YORK, ASSIGNOR TO GIFFORD-WOOD COMPANY, OF HUDSON, NEW YORK, A CORPORATION OF NEW YORK

TRAVERSING HOIST

Application filed March 23, 1928. Serial No. 264,165.

This invention relates to traversing hoists of the trolley bucket type, and among other objects, aims to improve the operation of such buckets, particularly when suddenly started and stopped.

Referring to the drawings showing a preferred embodiment of the invention,—

Fig. 1 is a sectional elevation of a trolley embodying the invention, a part of the monorail which supports it also being shown;

Fig. 2 is an end elevation of the trolley, the monorail being in cross-section;

Fig. 3 is an elevation, on a greatly reduced scale, of a materials-handling plant employing a dumping hoist bucket, which is supported from the trolley of Fig. 1; and

Fig. 4 is a vertical section substantially on line 4—4 of Fig. 1.

In the operation of trolley buckets such as are described in the W. H. Towne application Ser. No. 146,890, filed November 8, 1926, and assigned to the assignee of this application, a reversible trolley engine actuates the trolley rope which is secured to the opposite ends of the trolley. When the motor is suddenly started, the trolley rope, which has been at rest, suddenly starts traveling, and jerks the trolley, from which the bucket is suspended by the hoist rope. The bucket when empty may weigh a ton or more, and may hold upwards of a ton of coal, sand, gravel or other heavy material. This heavy mass, together with the trolley, must be accelerated rapidly, in order to move the materials from one part of the plant to another with all possible speed. But the inertia of the loaded bucket and the trolley is very great, and puts a heavy momentary strain on the trolley rope, the sheaves which support and guide it, and the connections between the ends of the rope and the trolley. In most installations, there is some slack in the trolley rope, and when the bucket is suddenly started and stopped, this slack may be sufficient to cause the rope to jump out of the grooves of the drums of the trolley engine unit (as shown in the H. V. Hard- 50 ing application Ser. No. 194,842 filed May 27, 1927, assigned as aforesaid) which would make operation impossible until the rope was replaced. The present invention provides

resilient connections between the ends of the trolley rope and the trolley, so that there is no undue strain on said connections, and the trolley is accelerated and stopped without injury to the various parts and without danger of the rope jumping out of the grooves.

Referring specifically to the drawings, there is shown in Fig. 3 a materials-handling plant of the type shown in said W. H. Towne application, comprising an elevated monorail 10 from which the trolley 11 is suspended, a dump bucket 12 (of the construction of the A. C. Bennett Patent No. 1,741,123 dated Dec. 24, 1929), a hoist rope 13 for suspending the bucket from the trolley while permitting travel of the bucket with the trolley, a trolley rope 14, a series of material holding bins 15, and an engine house 16 in which the hoist engine and trolley engine (not shown) are operated. The bucket receives its load by gravity, preferably as shown in the C. M. Root Patent No. 1,808,972 dated June 9, 1931, and dumps it automatically after descending into one of the bins so far that the trip pads contact with the material to unlatch its bottom, as disclosed in said A. C. Bennett patent.

To cause the trolley to travel in opposite directions as the reversible trolley engine is operated, the ends of the trolley rope are connected to the opposite ends of the trolley, and its intermediate portion is driven by the trolley engine. For reasons explained above, the trolley rope is resiliently connected to the trolley. As shown in Fig. 1, the trolley rope 14 has swivel connections 17 with a rod 18 resiliently mounted on the trolley 11 for longitudinal movement. The rod 18 is shown extending through a tubular housing 19, whose ends are preferably closed by caps 20, and enclosing a pair of coil springs 21. The outer ends of the coil springs preferably abut the caps 20, while the inner ends of said springs abut two disks 22 fixed to rod 18 at such points that the springs are not compressed materially when the trolley is at rest. Thus a sudden jerk on the trolley rope will compress one spring or the other, without affecting the spring at the opposite end. The resistance offered by compression of a spring

21 is found to be ample to obviate the operating difficulties explained above. Obviously, other arrangements of the springs and rod are possible.

5 As described and claimed in said W. H. Towne application, the trolley shown is equipped with spring buffers to check and stop any oscillations of the bucket in the vertical plane of the monorail which are set up 10 by sudden starting and stopping of the trolley. These spring buffers are interposed between the bucket and the trolley and act when the trolley and bucket are close together, which is their usual position when traveling 15 horizontally. As disclosed in said W. H. Towne application, the trolley here carries a frame F at each end including two uprights 23 and a connecting bar 24 at the lower ends of uprights 23. Two upright rods 25 are carried by the two uprights 23 and long springs 26 are carried on rods 25, bearing at their upper ends against abutments, and at their lower ends against sleeves 27 which are slidable 20 through the connecting bars 24 and are fast 25 at their lower ends to striker bars 28, against which the bucket strikes upon being elevated. As the striker bars 28 are transverse relative to the monorail, while the bail of the bucket is normally in the plane of the monorail, said 30 bail will strike both striker bars simultaneously, or if the bucket is swinging, the bail will strike first one bar and then the other, thus compressing the springs 26 which quickly 35 absorb the energy of the swinging bucket and bring it to rest.

Because of the inertia of the bucket when the trolley is started, and equally because of the momentum of the bucket when it is attempted to stop the trolley, the bucket will 40 move relative to the trolley, lagging behind the trolley at the start, and swinging ahead of it when the trolley is stopped. This pendulum-like swinging of the bucket is very quickly damped by the spring buffer construction shown in Figs. 1 and 2,—an important result when it is realized that were the swinging not checked, the bucket when lowered would dash itself against the inside 45 walls of the bins, with serious injury probably resulting.

It has been discovered that when the spring buffers as shown in the W. H. Towne application are combined in the same structure with the resilient trolley rope connections previously described, a much improved operation results which can only be attributed to the conjoint action of both spring shock absorber mechanisms. The resilient initial pull 55 of the trolley rope does not create nearly so 60 pronounced a tendency to swing the bucket as does a relatively inflexible connection between the trolley rope and trolley. What small swinging is imparted to the bucket is immediately checked. And when stopping 65 the bucket, there is the same conjoint, co-op-

erative action of the parts, both the horizontal and the vertical springs aiding in a smooth, easy stop of the bucket in a minimum of time, and without continual swinging.

At one end of the monorail, as shown in 70 Figs. 1 and 2, or at both ends as will be understood, there are abutments or stops 29, preferably secured to the monorail and extending below it in the path of a bumper plate 30 carried by either or both ends of rod 18. As 75 shown, the abutments or stops 29 are bifurcated (Fig. 4) to permit the trolley rope to pass through them without contact, which would quickly wear out the rope. When the trolley reaches either end of the monorail, or some point beyond which it should not travel, the bumper plate will strike the stop 29, thus compressing the spring 21 which then serves as a buffer spring; cushioning the shock. Any 80 tendency of the bucket to swing at this time will be checked by the frame carried springs 26, which again co-act with the resilient trolley rope connection.

85 The present application is an improvement 90 on a co-pending application filed by me May 12, 1927, Serial No. 190,933.

Obviously, the present invention is not restricted to the particular embodiment thereof herein shown and described. Moreover, it is not indispensable that all the features of the invention be used conjointly, since they may be employed advantageously in various 95 combinations and sub-combinations.

What I claim is:—

1. In a traversing hoist, the combination 100 of a trolley; a trolley rope secured at the ends to the trolley; a hoist bucket suspended from the trolley by a hoist rope and having a sheave movable along the hoist rope when the trolley travels; a buffer depending from 105 the trolley and engaged by the bucket to check such swinging thereof as is set up by starting and stopping; and yielding connections between the trolley rope ends and the trolley to accelerate or decelerate the trolley smoothly. 110

2. A traversing hoist comprising, in combination, a trolley; a rope connected to opposite ends of the trolley; a pair of springs carried by the trolley and connected with the rope so that the strain of a sudden jerk on the rope is largely absorbed by one of the springs; a hoist rope carried by sheaves on the trolley; a bucket suspended from the trolley by the hoist rope and having a sheave to travel over said rope as the trolley travels; and a resilient buffer mounted on the trolley and engaging the bucket when elevated subjacent the trolley so as to dampen swings of the bucket in the vertical plane of its line of travel. 120

3. A traversing hoist comprising, in combination, a trolley; a trolley rope; a resilient structure carried by the trolley and connected to the trolley rope at its ends so as to minimize the strain of sudden starting and stop- 130

ping; and a stop adjacent the track on which the trolley travels and constructed and arranged to be engaged by the aforesaid resilient structure, which then serves as a buffer.

5 4. A traversing hoist comprising, in combination, a trolley; a trolley rope; a rod extending longitudinally of the trolley; a pair of coil springs surrounding the rod; a housing on the trolley enclosing the rod and the
10 springs; caps at opposite ends of the housing adjacent which the springs press; disks secured to the rod at intermediate points and providing abutments for the inner ends of the springs; connections between the trolley rope
15 ends and the rod; the rod extending outside the housing at one end and carrying a bumper plate; and a stop fixed adjacent the track on which the trolley travels so as to be engaged by the bumper plate when the trolley reaches
20 one limit of its travel.

In testimony that I claim the foregoing as my own I have hereto affixed my signature.

CLARENCE C. BRINLEY.
